UNITED STATES PATENT OFFICE.

JONATHAN CRABTREE, OF PHILADELPHIA, PENNSYLVANIA, ASSIGNOR TO DORNAN, MAYBIN & CO.

DESIGN FOR A CARPET-PATTERN.

Specification forming part of Design No. 5,563, dated March 5, 1872.

SPECIFICATION.

I, JONATHAN CRABTREE, of the city of Philadelphia, county of Philadelphia, State of Pennsylvania, have invented and produced a new and original Design for Carpets, of which the following is a specification:

The nature of my design is fully represented in the accompanying photographic illustration, to which reference is made.

Claim.

I claim as my invention—
The design for a carpet, as shown.
JONATHAN CRABTREE.
